CLAIM

The ornamental design for a cat litter box with handle, as shown and described.

DESCRIPTION

FIG. 1 is a perspective view of a cat litter box with handle showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the cat litter box with handle that form no part of the claimed design.

1 Claim, 7 Drawing Sheets
